Fig. 4

Fig. 5

FIGURE 1 is a perspective view of a ladder display stand of my design showing generally the front and left-hand end thereof;

FIGURE 2 is a top plan view of the display stand of my design;

FIGURE 3 is an elevational view taken from one end thereof;

FIGURE 4 is an enlarged fragmentary view of a portion of the upper crossbar as seen in FIGURE 2;

FIGURE 5 is a cross sectional view taken along the line 5—5 in FIGURE 4;

FIGURE 6 is an enlarged fragmentary view of a portion of an end upright member as seen in FIGURE 3;

FIGURE 7 is a cross sectional view taken along the line 7—7 of FIGURE 6;

FIGURE 8 is a cross sectional view taken along the line 8—8 of FIGURE 2; and

FIGURE 9 is a view taken along the line 9—9 of FIGURE 8.

This is a division of design application Ser. No. 9,242, filed Nov. 1, 1967.

I claim:

The ornamental design for a ladder display stand, as shown.
